SHOE SEWING MACHINE

Carl F. Whitaker, Beverly, Mass., assignor to
United Shoe Machinery Corporation, Borough
of Flemington, N. J., a corporation of New
Jersey

Application November 1, 1939, Serial No. 302,382

8 Claims. (Cl. 112—46)

The present invention relates to methods of handling a welt strip having one edge divided into flaps, while being sewed to the marginal portion of a shoe upper, and to improvements in machines for performing the required sewing operations.

In the manufacture of pre-welt shoes, it is usual to sew a welt strip to the marginal portions of each shoe upper, the welt being bent widthwise at right angles to the upper in order to attach the outsole. Where storm welts are employed in the construction of a pre-welt shoe, it sometimes is the practice to divide into three flap-like parts one edge of the welt which is to be sewed to the upper, the marginal portion of the upper being inserted between two of the parts before sewing. The flap parts of the welt are then permanently formed before sewing by bending the third remaining part along the divided edge of the welt through right angles to the flaps which are to be sewed to the upper in a separate bending operation. In this way, the third part can be kept clear of the seam while attaching the upper. After sewing the welt to the upper, the shoe is completed in a manner described more fully in U. S. Letters Patent to Arnold No. 2,039,287, dated May 5, 1936.

In sewing the welt to the upper in this way, the only surface available for guiding the welt is along the edge of the third flap-like part. When sewing a welt having a divided edge, a more uniform seam may ordinarily be formed if the full thickness, undivided edge of the welt is guided by an edge gage to direct the welt with relation to the stitch-forming devices of the sewing machine. When the full thickness, undivided edge of the strip is so guided, it is unnecessary to form the welt permanently beforehand, one flap-like part being deflected only temporarily while sewing, and led clear of the seam which passes through the other parts. The only difficulty in sewing a divided welt in this manner is that by temporarily deflecting one flap-like part to clear the seam, the other parts are also deflected slightly with respect to the undivided edge. Thus the undivided edge is forced somewhat out of the plane of either of the remaining divided parts and, if an edge gage of ordinary construction is used along the undivided edge, it is difficult to guide the deflected welt accurately with respect to the stitch-forming devices because of the tendency for the undivided edge under edgewise pressure to become deflected still further from the parts at the divided edge. Accordingly, the objects of the present invention are generally to

simplify and improve the operations of sewing a welt to the marginal portion of a shoe upper, which welt is divided along one edge and deflected widthwise temporarily out of the plane of the other undivided edge, and particularly to prevent further deflection widthwise in such a welt while guiding it into line with the stitch-forming devices of a sewing machine during the formation of a seam.

With these and other objects in view, one feature of the invention is to provide a welt guide in a sewing machine for directing and supporting in angular relation to the work supporting surfaces of the work support and presser-foot of the machine, a surface at one edge of a welt strip, cut along its opposite edge parallel to the side surface to divide said opposite edge into flaps, at least one of which flaps is applied and sewed to the marginal portion of a shoe upper, and the remaining flap of which is temporarily deflected at an angle clear of the seam while sewing. By providing a guide for supporting the undivided edge of the strip in this manner, an improvement in uniformity and strength of the seam results so that it is possible to construct a stronger shoe of this type having a more nearly uniform appearance than heretofore.

Another feature of the invention is to provide an improved method of sewing a divided welt strip to the marginal portion of a shoe upper in which one flap of the divided welt edge is temporarily deflected widthwise clear of the seam and the undivided edge is guided along its outer edge surface and is supported along one side to prevent the welt from being deflected still further widthwise as a result of the guiding action.

When a welt strip having one divided edge is sewn to the marginal portion of a shoe upper with one of the divisions deflected at an angle to another, the deflected part may cover up otherwise accessible portions of the stitch forming devices in the sewing machine employed so that it is inconvenient to sever the threads manually at the end of a seam, thus rendering it difficult to free the completely sewed shoe parts from the machine. A machine for performing such sewing operations may be provided with a work support detachably secured to the frame of the machine, the work support having elongated perforations or slots to receive the work penetrating instruments, as more fully described in U. S. Letters Patent to Merrick No. 490,854 of January 31, 1893. When such machines are stopped, the main sewing shaft is rotated manually until the work penetrating instruments are withdrawn

from the work. These instruments may include one or more hook needles acting from beneath the work support through the perforations therein, and when the needles are withdrawn, loops of thread are carried in the hooks through the perforations of the work support. Where light threads are used, the practice is to pull the work forcibly from the work support, causing the threads to be broken in the hooks of the needles, but where heavy threads of good quality are utilized, there is danger of injury to the work or to the machine when the threads are thus broken.

A further object of the invention, therefore, is to provide a simplified and improved thread cutter which will operate effectively, particularly when the machine employed for this purpose is of the type indicated, having one or more hook needles arranged beneath the work support. To permit the work to be withdrawn from the machine after sewing without difficulty, according to a further feature of the invention a thread cutter comprising a knife having one or more loop spreading points sharpened along one edge only of each is mounted on the work support for movement in the line of feed past the perforations in the work support between the work support and the needles, thus causing the points to enter the loops carried by the needles and to sever one side only of each loop. By mounting the knife on the work support rather than on some other part of the machine frame, accurate alignment of the cutter points with the needle loops which pass through the perforations is insured, and the parts may be adjusted for proper alignment when the work support is completely removed from the machine. In the machine employed for this work, the needles are arranged to feed the work as well as to form the stitches, the back-feeding movement of the needles occurring after the needles are withdrawn from the work. In case the machine is not stopped in a definite position, the needles may come to rest at either an advanced or a retracted position in the line of feed. In connection with this feature of the invention, the knife is arranged to be given a movement in excess of the feeding movements of the needles so that the threads will be severed regardless of the exact position in which the machine is stopped.

These and other features also consist in certain constructions, combinations, and arrangements of parts hereinafter described and claimed, the advantages of which will be apparent to those skilled in the art from the following description taken in connection with the accompanying drawings in which Figure 1 is a view in side elevation of parts at the front of a shoe sewing machine embodying the features of the present invention, indicating in section the positions of a divided welt strip and upper while being sewn; Figure 2 is a plan view on an enlarged scale showing the relationship between the work support and the welt supporting guide of the machine illustrated in Figure 1; Figure 3 is a view in front elevation of the machine parts illustrated in Figure 1; Figure 4 is a plan view on an enlarged scale indicating the operation of the thread cutter; and Figure 5 is a sectional view illustrating the manner of severing the threads at the end of a seam.

As illustrated in the drawings, a machine for forming a double row chainstitch seam is provided with a pair of parallel straight hook needles 2 and a work support 4 having elongated perforations or slots 6 to receive the needles and permit

the needles to be moved in the direction of feed while engaging the work. The needles are both supported in a single needle bar 7 arranged to be actuated, as more fully illustrated and described in the Merrick patent referred to. During the operation of this machine, the work is clamped against the upper surface of the work support by a presser-foot 8 and the work support is L-shaped having the needle perforations 6 in one arm and the other arm detachably secured to the frame of the machine indicated at 10 by a tongue and groove connection and set screws 11. The needles reciprocate beneath the work support to penetrate the work while clamped, moving in the direction of feed while in engagement with the work to feed the work, and thereafter withdrawing from the work with loops of thread held in their hooks. After withdrawing from the work, the needles are back-fed the length of a stitch, and the operations are repeated.

The illustrated machine is equipped for sewing a welt strip 12 cut along one edge parallel to the grain surface 14 of the welt to form a series of flaps 16, 18 and 20. Between the flaps 16, 18 there is inserted the marginal portion of a shoe upper 22 so that when the welt is carried along the work support, parallel stitches will be inserted connecting the parts together. The third flap 20 of the strip is deflected from the flaps 16, 18 and is led clear of the seam solely by engagement with the rearward edge of the work support. After the parts have been completely sewn together throughout the length of the upper marginal portion, an outsole is attached to the full thickness edge of the welt, the flap 20 being cemented or otherwise secured to the same surface of the outsole along with the full thickness edge of the welt. When the flap 20 is deflected during sewing from the remaining parts of the welts, the undivided full thickness edge also is deflected slightly out of the plane of the flaps 16, 18 so that it is difficult to guide the undivided edge accurately with the use of an edge gage having the usual construction.

To guide and support the undivided edge of the welt in angular relation to the flaps at the other edge and to the work supporting surface of the work support, according to the present invention a guide block 24 is adjustably mounted in spaced relation to the work support on a horizontal clamp bolt 26 carried by a vertically adjustable bar 28 secured at its lower end to the machine frame 10, the axis of which bolt extends substantially parallel to the seam line formed by the machine. The guide block carries at right angles to its supporting surface a gage roll 30 along which the outer surface of the undivided welt edge passes. To prevent further deflection in a widthwise direction of the welt strip as a result of pressure of the undivided edge against the roll 30, the side surface of the undivided edge is supported by a flat upper surface on the block having its edge adjacent the work support at substantially the same level as the work support, the welt being thus held accurately in position with respect to the lines of sewing. The flap 20 which passes between the work support and the guide block 24 also presses yieldingly against the edge of the work support, causing the welt to be held more firmly in place against the guide 24 and roll 30.

When the clamp bolt 26 is loosened, the block 24 which fits within an opening at the upper end of the bar 28 may be rotated about the bolt as a

pivot so that the upper welt supporting surface of the block may be located in a position parallel to that naturally assumed by the side surface along the undivided welt edge as a result of widthwise deflection of the third flap 20. To move the gage roll 33 towards or from the work support, the block 24 is slotted to receive the bolt 26. Also, the bar 28 may be adjusted vertically by loosening a pair of bolts 32 which pass through vertical slots at the lower end of the bar to secure it to the frame 10.

When sewing together the parts of a shoe constructed in the manner indicated substantially all of the operating parts including the needles beneath the work support are covered at one side by the upper 22 and at the other side by the downwardly deflected flap 28 of the welt strip so that access to the parts is rendered difficult. When the machine is brought to rest, the needles are withdrawn carrying loops of thread in their hooks, so that in order to remove the work conveniently the threads must be disengaged from the needles. If the work is forcibly withdrawn from the work support, the threads will be broken along that portion engaged by the needles, but in so doing the needles may become bent or other associated parts damaged.

In order to disengage the work from the work support conveniently at the end of a seam, in the present machine there is pivotally mounted on the work support a thread cutter comprising a knife 34 (see Fig. 4) having a pair of loop spreading points sharpened along an edge of each to enter the loops of thread carried by the needles, and to sever one side of each loop which is connected to the work as shown in Figure 5. By means of the knife, the threads are severed close to the under surface of the work, the ends of the threads remaining attached to the machine being readily disengaged from the needles.

The knife 34 is secured to an upwardly projecting arm of a lever 36 having a fulcrum stud 38 clamped in the downwardly extending arm of the work support 4. The other arm of the lever extends rearwardly and laterally of the work support and forms a manually operable handle with which to actuate the cutter, a spring 40 connected between the work support and the lever being provided to maintain the cutter in inoperative position. When the end of a seam is reached, the machine is actuated manually to carry the threaded needles beneath the work support through the elongated perforations. When the needles are withdrawn, the threads are stretched tightly so that little or no effort is required to sever them.

Due to the work feeding and back feeding movements which are imparted to the needles, unless a definite effort is made to stop the machine uniformly in exactly the same position at the end of the sewing, the positions of the loops of thread carried by the needles when free of the work may vary substantially, thus rendering it difficult to sever the threads accurately between the perforations in the work support and the needles. To avoid substantial variation in the lengths of thread ends remaining attached to the work, the pivotal mounting of the lever 36 is located as far as possible from the perforations in the work support, and the arrangement of the knife 34 is such that a swinging movement of relatively long radius is imparted to the knife so as to carry it along the line of feed close to the under surface of the work support, through

a distance substantially in excess of the feeding movements of the needles.

The nature and scope of the invention having been indicated, and a particular embodiment of the invention having been specifically described, what is claimed is:

1. A sewing machine having, in combination, stitch forming devices, a work support, a presser foot and a welt guide having angularly disposed vertical edge and welt side surface engaging elements, the side surface engaging element being mounted in angular relation transversely of the welt to the work supporting surface of the work support with its adjacent edge at substantially the same level with the work support for directing and supporting one edge of a welt strip cut along its opposite edge parallel to the grain surface to divide said edge into separate flaps, at least one of which is applied to the marginal portion of a shoe upper to be sewn thereto, the edge engaging element on the guide being located to deflect the remaining flap at an angle clear of the seam against the work support by pressure on the welt edge of the edge engaging element.

2. A sewing machine having, in combination, stitch forming devices, a work support, a presser foot, a welt guide spaced from but with its adjacent edge at substantially the same level as the work support for supporting in angular relation to the work supporting surface of the work support one edge of a welt strip cut along its opposite edge parallel to the grain surface to divide said edge into separate flaps, at least one of which flaps passes towards the point of operation of the stitch forming devices along the work support to secure thereto the marginal portion of a shoe upper, and an edge engaging element on the guide located to deflect the remaining flap at an angle clear of the seam against the work support and to cause said remaining flap to pass through the space between the work support and the welt guide.

3. A sewing machine having, in combination, stitch forming devices, a work support, a presser foot, a welt guide for directing and supporting in angular relation to the work supporting surface of the work support one edge of a welt strip cut along its opposite edge parallel to the grain surface to divide said edge into separate flaps at least one of which is applied to the marginal portion of a shoe upper to be sewn thereto and the remaining flap of which is bent at an angle to clear the seam, and a vertically adjustable bar on which the welt guide is pivotally mounted to adjust the angle of the guide in parallel supporting relation to the undivided edge of the welt strip.

4. The method of controlling a welt strip having one edge divided into two or more parallel flaps and another undivided edge, while sewing certain of the flaps to the marginal portion of a shoe upper, which consists in leading one or more of the flaps together with the marginal portion of the upper along a work support into the line of operations of a sewing machine, deflecting another flap of the divided edge to clear the sewing line, directing the outer surface of the undivided edge and supporting a side of the undivided edge at an angle to all the flaps of the divided edge to prevent the welt from being deflected still further widthwise as a result of the guiding action.

5. The method of controlling a welt strip having one edge divided into three flaps and another undivided edge while sewing the marginal portion

of a shoe upper between two of the flaps which consists in leading two of the flaps with the upper disposed between them along a work support into the line of operations of a sewing machine, deflecting the third flap clear of the sewing line, directing the outer surface of the undivided welt edge and supporting the side of the undivided edge along a surface disposed at the angle naturally assumed by the undivided edge as a result of deflecting the third flap to prevent displacement of the flaps being sewn to the upper from the sewing line.

6. A sewing machine having, in combination, a main frame, a work support detachably secured to the frame and provided with a work engaging surface, a presser-foot, stitch forming devices including a straight hook needle arranged beneath the work engaging surface of the work support, and a thread cutter mounted for movement on the work support comprising a knife provided with a loop spreading point to enter the loop of thread carried by the needle and sever one side only between the work supporting surface of the work support and the needle at the end of a seam.

7. A sewing machine having, in combination, a main frame, an L-shaped work support, one arm of which is detachably secured to the frame and the other arm of which is perforated and pro-

vided with a work supporting surface, a presser foot, stitch forming devices including a straight hook needle arranged beneath the work supporting surface of the work support to enter the perforation in the work support when penetrating the work, and a thread cutter comprising a knife provided with a loop spreading point, and a lever on which the knife is mounted fulcrumed on the work support to swing between the work engaging arm of the work support and the needle when the needle is free of the work across the path of thread extending between the perforation in the work support and the needle.

8. A sewing machine having, in combination, stitch forming devices including a hook needle arranged to penetrate the work, to feed, to withdraw from the work, and to back-feed while free of the work, and a thread cutter comprising a knife and a lever on which the knife is mounted fulcrumed for swinging movement along the line of feed against the thread carried by the needle when free of the work, said swinging movement being in excess of the needle feeding movement to insure severing the thread between the work and the needle at the end of a seam, regardless of the feeding position of the needle.

CARL F. WHITAKER.
